UNITED STATES PATENT OFFICE.

NATHAN L. HOLMES, OF RACINE, WISCONSIN.

CIRCLE-IRON FOR WAGONS.

SPECIFICATION forming part of Letters Patent No. 337,404, dated March 9, 1886.

Application filed July 11, 1885. Serial No. 171,380. (No model.)

To all whom it may concern:

Be it known that I, NATHAN L. HOLMES, of Racine, in the county of Racine and State of Wisconsin, have invented certain new and useful Improvements in Circle-Irons for Wagons; and I do hereby declare that the following is a full, clear, and exact description thereof, reference being had to the accompanying drawings, and to the letters of reference marked thereon, which form a part of this specification.

This invention relates to improvements in circle-irons for wagons; and it consists in the matters hereinafter described, and pointed out in the appended claims.

In a prior application for Letters Patent, Serial No. 148,640, made by me upon the 24th day of November, 1884, a circle-iron is shown and claimed which, instead of being made of one continuous rod or bar, is constructed in three separate pieces, comprising two side pieces, connected at their front ends with the hounds and sustained at their rear ends by means of two circle-posts, which are attached to the hounds and support a third transverse piece extending between and attached to the said posts. In the particular form of devices shown in said patent as one desirable way of constructing and attaching a sectional circle-iron of the kind above mentioned the circle-iron is square in cross-section, and the parts thereof are attached to the posts by engagement with clamping devices upon the latter. It is sometimes desired, however, to employ round instead of square iron for the circle, and inasmuch as the particular clamping devices illustrated in said patent are not well adapted for holding round iron, and the forging or shaping of the ends of round iron to adapt them for engagement with the said clamping devices would involve undesirable expense, means are herein shown and claimed more especially adapted for connecting with the circle-posts circle-iron sections of circular cross-section, or those which are round upon their ends.

A device embodying one important feature of this invention consists in a three-part circle-iron and supports therefor, the parts of the circle-iron and the posts being constructed with screw-threaded joints for attachment to each other.

The invention also embraces other matters, as will hereinafter appear.

In the accompanying drawings, illustrating my invention, Figure 1 is a plan view of the axle-hounds and a circle-iron embodying my invention. Fig. 2 is a sectional view of one of the posts supporting the circle, taken upon line *xx* of Fig. 1. Fig. 3 is a horizontal section of the upper part of said post, taken upon line *xx* of Fig. 2. Fig. 4 is a sectional view illustrating the connection between the forward end of the circle with the hounds, taken upon line *yy* of Fig. 1. Fig. 5 is a similar sectional view showing a modified form of the device shown in Fig. 4. Fig. 6 is a detail view showing another form of the upper part of a post such as is shown in Fig. 1.

As herein illustrated, A A indicate the axle-hounds, which are connected at their rear ends by a straight sway-bar, A'; B, the circle, herein shown as circular in cross-sectional form, and C C are the posts which support the rear portion of the circle from the hounds, said posts being located at or near the points at which the circle intersects the hounds.

D D are vertical bolts passing through the posts and hounds for securing said posts in place, and E E are castings used for attaching the forward ends of the circle-iron to the hounds.

The circle is composed of three separate pieces, sections, or bars, B' B' B'', of which the sections B' B' form side pieces, extending from the front parts of the hounds to the circle-posts, and the bar B'' a transversely-arranged part extending between the said posts. The said bar B'' is, as herein shown, made of straight form between its two points of support; but it may be curved to give the usual continuous circular form to the entire circle, if desired.

As far as described, the parts mentioned are constructed, generally, as set forth in the prior application above referred to. In this case, however, the circle-iron being round, means are provided for attaching the parts of the circle to the posts and to the castings E, as follows: The posts C are provided with axial apertures *c*, through which pass the bolts D, said bolts being headed at their upper ends, and extended through the hounds A and provided with suitable nuts at their lower ends. The said posts are constructed, also, with laterally-

projecting parts or heads C' C', provided with | threaded sockets c', adapted to receive the threaded ends b b' of the circle-sections B' B' B'. The said projections are preferably made 5 to form a continuous curve, and are cast hollow or tubular, to decrease the weight of the posts, the interior diameter of the cavity being desirably made somewhat larger than that of the sockets c', so that the screw-threads may 10 be readily cut in the latter. The construction of the sockets in the particular manner shown is not, however, essential, inasmuch as the said sockets may be otherwise formed in the posts, or in projecting parts thereof, with the 15 same general results as are obtained by the construction herein shown.

The castings E, by which the parts or bars B' B' of the circle are connected at their forward ends with the hounds, are preferably 20 made with forwardly-projecting parts E', which are placed against and bolted to the hounds, and are provided at their upper ends with screw-threaded sockets e, for engagement with the threaded forward ends, b', of the bars B' 25 B'. The main portions or standards of the said castings are desirably cast hollow, as shown, to decrease the weight of the castings, and to facilitate the threading of the sockets e.

As shown in Figs. 1 and 5, the sockets e e of 30 the castings E are vertical, and the forward ends of the bars B' B' bent downwardly to properly engage the sockets. In the form of the casting E shown in Fig. 4, however, the upper end of the said casting is made of curved 35 shape, and the socket e therein is arranged horizontally and in the same plane with the circle, so that the ends of the bars B' B' are in this case not bent downwardly.

When the sockets of the posts C are arranged 40 relatively to the bars B' B' as is shown in Figs. 1 and 2, the form of the castings E shown in Fig. 5 is preferably used, inasmuch as the engagement of the downwardly-bent ends of the said bars with the said castings obviates 45 liability of the bars being turned in their sockets by upward or downward pressure applied to the middle curved portions thereof. In practice, however, the form of casting shown in Fig. 4 may be used by screwing up the parts 50 sufficiently tight to prevent their turning; or, by arranging the sockets c' c' of the posts at a considerable angle with reference to the sockets e e of the castings E, the end portions of the bars B' B' will stand at an angle with each 55 other, instead of being nearly or exactly in alignment, and said bars will thereby be prevented from turning in said sockets.

A construction is shown in Fig. 6 in which the section or bar B' of the circle is curved to 60 form a continuation of the curve of the bars B' B', and the projections C' C' of the posts are arranged nearly opposite each other, so as to bring the sockets therein in alignment with the circular curve of the bars B' B' and B'. 65 In this case it will be observed that the axes of the sockets c' will stand at a considerable angle to a straight line, connecting the ends of

the bars B' or B', so that neither of said bars can be shifted vertically by the turning of their ends in the said sockets.

70

In the exact construction of the parts herein illustrated the sockets c' and e of the posts C and castings E are reamed out or otherwise made smooth in their outer portions to fit the adjacent unthreaded or cylindric portions of 75 the circle-iron sections or bars, so that the threaded parts of the said bars may entirely enter the sockets.

It is often desirable in putting together the parts of the circle and its supports that the 80 bars B' and B' should be screwed to a greater or less distance into the sockets, in order to accurately adjust the distances between the posts and the castings E, and to bring the parts into proper relative position, and one 85 object of the construction in the sockets above set forth is to enable this to be accomplished without exposing any portion of the screw-threads thereon.

Among other advantages of this feature of 90 construction, it will be noted that the entrance of the unthreaded or full-sized portions of the bars into the sockets greatly strengthens the parts, inasmuch as it obviates liability of the bars breaking at the points where they are reduced in diameter at the beginning of the screw-thread and where they emerge from the 95 sockets.

95

The construction described also has the advantage of giving a neater and smoother appearance at the joints between the bars and the sockets than would be the case if a portion of the screw-thread were visible.

100

It is to be understood that the appended first, second, and third claims are intended to 105 cover the devices therein set forth as one way of carrying out the invention broadly claimed in the first claim of my said prior application, Serial No. 148,640.

105

The features of construction set forth in the 110 appended claims other than those mentioned are, however, capable of use in connection with other forms of circle-irons than the particular one shown in this and in said prior application, and said last-mentioned claims are 115 therefore intended to cover the devices therein set forth without limitation to the use of said devices in connection with the particular features of construction in other parts of the device illustrated and described herein. It is to 120 be understood, also, that all of said claims cover the parts or elements set forth therein when said parts are constructed in such manner as to obtain either any or all of the advantages, purposes, or functions obtained by or belonging 125 to said parts or elements in the particular construction thereof herein shown.

115

I claim as my invention—

1. The combination, with the hounds of a wagon and two circle-posts for supporting the 130 rear part of the circle from the hounds, of a circle comprising two side bars connected at their front ends with the hounds and at their rear ends with the posts, and a transverse

130

135

bar located between the said posts, said several bars being attached to the posts by screw-connections, substantially as described.

2. The combination, with the hounds of a wagon, of posts, each provided with two screw-threaded sockets, and a circle comprising two side bars and a rear transverse bar, said several bars having their ends screw-threaded and engaged with the said sockets, substantially as described.

3. The combination, with the hounds, of two circle-posts for supporting the rear portion of the circle from the hounds, castings E, for connecting the forward ends of the side bars with the hounds, and a circle comprising two side bars and a rear transverse bar, said several bars being connected at their ends with the said posts and castings by screw-threaded joints, substantially as described.

4. The combination, with the hounds and a circle made in two or more parts screw-threaded upon their adjacent ends, of a circle post provided with a longitudinal bolt-aperture, and with screw-threaded sockets to receive the adjacent ends of the parts of the circle, and a bolt inserted through the post and hounds, substantially as described.

5. The combination, with the hounds and a circle made in two or more parts, of a circle-post provided with projecting parts C' C', cast hollow and provided with screw-threaded sockets c' c', the adjacent ends of the parts of the circle being screw-threaded to engage said sockets, substantially as described.

6. The combination, with the hounds and a circle made in two or more parts screw-threaded upon their adjacent ends, of a circle-post

having a longitudinal bolt-passage, c, and provided upon its upper end with lateral projections C' C', formed upon a continuous curve, 40 cast hollow and having screw-threaded sockets c' c', and a bolt for securing said post to the hounds, substantially as described.

7. The combination, with the hounds and a circle screw-threaded upon its forward ends, 45 of castings E, for connecting the circle with the hounds, said castings being provided with parts E', for attachment to the hounds, and having screw-threaded sockets at their upper ends for engagement with the ends of the circle, 50 substantially as described.

8. The combination, with the hounds and a circle screw-threaded upon its forward ends, 55 of castings E, for connecting the circle with the hounds, said castings being cast hollow and provided with screw-threaded sockets e, and having parts E', for attachment to the hounds, substantially as described.

9. The combination, with a circle made cylindric and screw-threaded at its ends, and 60 posts or other supports for the circle, provided with sockets for the ends of the circle, said sockets being screw-threaded in a portion of their length only, and constructed to extend over the adjacent unthreaded parts of the circle, substantially as and for either any or all of the purposes set forth.

In testimony that I claim the foregoing as my invention I affix my signature in presence of two witnesses.

NATHAN L. HOLMES.
